UNITED STATES PATENT OFFICE.

ALBERT WILFORD, OF LANSDOWNE, MARYLAND.

CONVEYER.

Application filed November 1, 1924. Serial No. 747,281.

To all whom it may concern:

Be it known that I, ALBERT WILFORD, a citizen of the United States, residing at Lansdowne, in the county of Baltimore and State of Maryland, have invented new and useful Improvements in Conveyers, of which the following is a specification.

My present invention pertains to conveyers and more particularly to the type of 10 conveyers employed in connection with grain elevators for delivering grain therefrom to vehicles of various kinds, the conveyer constituting the subject of my Patent 1,094,508 of April 28, 1914 being an example of said 15 type.

The object of my present invention is the provision of the conveyer adapted in general to be easily handled and characterized particularly in the capacity of the tubular 20 conveying means to be easily increased or diminished in length without subjecting the parts to undue wear so that the lifetime of the tubular conveying means will be materially prolonged.

25 To the attainment of the foregoing, the invention consists in the improvement as hereinafter described and definitely claimed.

In the accompanying drawings, forming part of this specification:—

30 Figure 1 is a general view of the conveyer constituting the preferred embodiment of my invention.

Figure 2 is a sectional view, on an enlarged scale, illustrative of the tubular conveying means.

Figure 3 is an enlarged detail elevation of the same.

Figure 4 is a transverse section taken in the plane indicated by the line 4—4 of Figure 3.

Figure 4^a is a top plan view illustrative of the upper end of the intermediate, adjustable tubular conveyer section.

Figure 5 is a cross-section of the same.

45 Figure 6 is a view of one of the cable control devices.

Figure 7 is a detail view of the other cable control device.

Similar numerals designate corresponding 50 parts in all of the views of the drawings.

I show in Figure 1 an elevator building 1, and I also show a crane 2 projecting from said building and having a revolute spout 3.

55 My novel conveyer is hingedly connected at 4 to said spout 3, and the upper section of the conveyer is in the form of a tapered

head 5. A safety chain 6 is interposed between and connected to the building 1 and the head 5, but said safety chain does not act unless the hinge 4 breaks whereupon the 60 safety chain will prevent gravitation of the conveyer.

Fixedly connected at 6^a to and surrounding the lower portion of the head 5 is a tubular casing 7, and connected to the casing 7 65 is a cable 8 which extends over guides 9 on an overhanging arm 10 carried by the building 1 and is designed to be connected with the drum 11 of the device shown in Figure 6, the said device being of the construction 70 illustrated or of any other construction adapted to take up and let off the cable 8 and adjustably hold the same.

Arranged within the casing 7 and appropriately connected at its upper end to the 75 lower end of the head 5 is an inner tubular conveyer section 12. The connection between said inner section 12 and the lower end of the head 5 is designated by 13, and it will be readily noted from Figure 2 80 that the tubular conveyer section 12 is spaced from the casing 7.

At 14 is an intermediate tubular conveyer section which surrounds the section 12 and is interposed between said section 12 and the casing 7 and is endwise adjustable so that the tubular conveyer can be increased or diminished in length as occasion demands. Any appropriate means may be employed to move the section 14 endwise upwardly or to 90 permit said section 14 to gravitate relative to the casing 7 and the inner section 12. I prefer, however, to connect a cable 15 to the section 14, as designated by 16 in Figure 1, and to carry the said cable 15 over a guide 17 95 on the head 5, and to connect the cable to the drum 18 of the device shown in Figure 7, said device being adapted for the taking up of the cable 15 and for the letting off of the same, and being also adapted to adjustably hold the cable 15 so as to retain the tubular section 14 in the relative position desired.

As will be understood by comparison of Figures 3 and 4 of the drawings, the casing 7 is provided at its lower end with rollers 20 which extend within the plane of the wall of the casing and are adapted by engaging the section 14 to prevent undue wear of either the casing 7 or the section 14 incident to endwise movement of the section 14 in the casing 7. It will also be understood that the said rollers 20 will ease the movement 105 110

of the section 14 relative to the casing 7 so that but little effort will be required for the raising of the section 14, and there will be no liability of the section 14 "sticking" when it is desired to permit gravitation or downward endwise movement of the section 14.

As best shown in Figures 2 and 4^a and 5 the section 14 is provided at its upper ends 10 with rollers 30 which extend at opposite sides of the plane of the wall of section 14 and are designed by engaging either the tubular section 12 or the casing 7 to prevent sticking of the section 14 and at the 15 same time render easy the raising of the section 14 while lessening liability of wear of either the section 14 or the section 12 or the casing 7. As illustrated the rollers 30 are spaced apart and are loosely mounted 20 on a ring 31, carried in a barrel 32 of an annulus 33, fixed to the section 14, the said annulus being notched, at 34, for the play of the rollers 30, and the barrel 32 being disposed at opposite sides of each roller 30 25 so that the rollers are adequately maintained in spaced relation and hence are adapted to operate to the best advantage for the purpose stated.

It will be manifest from the foregoing 30 that by virtue of the rollers 20 and 30 ease of movement of the section 14 will be assured and at the same time frictional wear of the casing 7 conveyer section 12 and conveyer section 14 will be reduced to a minimum.

I have specifically described the structure in the preferred embodiment of my invention in order to impart an exact understanding of the said structure. I do not desire, 40 however, to be understood as confining my

self to the disclosed structure, my invention being defined by my appended claims within the scope of which structural changes may be made without departure from my invention.

Having described my invention, what I claim and desire to secure by Letters-Patent, is:—

1. In a conveyer of the character disclosed, the combination with a tubular conveyer section, of a casing surrounding the same, another tubular conveyer section slidably mounted between the first section and the casing, rollers carried by the casing and arranged to contact with the slidable section, and rollers carried by the slidable section and operable between the first-named tubular conveyer section and the casing. 55

2. In a conveyer of the character disclosed, the combination with a tubular conveyer section, of a casing surrounding the same, another tubular conveyer section slidably mounted between the first section and the casing, rollers carried by the casing and arranged to contact with the slidable section, and rollers carried by the slidable section and operable between the first-named tubular conveyer section and the casing; 60 each set of rollers being arranged in a circular series. 65

3. In a conveyer of the character set forth, the combination of a tubular conveyer section, an annulus fixed to said section at one end thereof and having a barrel, said annulus notched at intervals, a ring carried in the barrel of the annulus, and rollers loosely mounted on said ring and disposed in said notches. 75

In testimony whereof I affix my signature.

ALBERT WILFORD.
